RANGE WITH FRONT-SERVICEABLE BACKSPLASHER

George R. Sherman, Louisville, Ky., assignor to General Electric Company, a corporation of New York
Filed Feb. 9, 1960, Ser. No. 7,682
6 Claims. (Cl. 126—214)

The present invention relates to a range, either electric or gas with a novel backsplasher design for ease in servicing the range from the front without moving the range away from the wall. Front servicing is advantageous to the serviceman because all components are in open view which provide ample working space for testing and replacement of the components.

This invention is particularly concerned with hinge means for the backsplasher. Hinged backsplashes are known in the prior art but they are usually provided with a removable back cover for gaining access to the interior thereof. Each year more and more controls are being added to the deluxe ranges for obtaining automatic temperature control of the heating elements in the cooktop as well as the heating elements of the oven. Many such automatic controls include indicator dials which are mounted on the shaft of the controlling units and are covered with a shield so that only a portion of the dial may be read at any one time. The introduction of such automatic controls and dials has complicated the construction of the backsplasher and in some instances has increased the difficulty of servicing the range.

The principal object of the present invention is to provide a range with a hinged backsplasher that may be folded down over the cooktop while it is stored in its shipping carton, and may be opened up for servicing by merely pivoting the several segments of the backsplasher into convenient positions for testing and repairing.

A further object of the present invention is to provide a range with a triple-hinged backsplasher that has a hinge means that is common to all pivoted portions of the backsplasher for ease in servicing the range from the front.

A still further object of the present invention is to provide a backsplasher with a front crystal that is easy to clean by recessing the shafts of the control components so that once the control knobs are removed the crystal is unobstructed.

A range embodying the present invention will have a backsplasher arranged across the back of the cooktop. For ease in shipping the range so as to obtain the most compact design so that the maximum number of ranges may be loaded into a railway box car, the entire backsplasher is folded down over the cooktop to lie in a horizontal position before it is placed in its shipping carton. Once the range is unpacked the backsplasher will be raised to its vertical position and fastened in place. The backsplasher includes three pivoted portions: a back cover plate, an instrument mounting panel or bracket for supporting the various controls for the heating units on the surface of the cooktop as well as in the oven, and finally a front trim frame for supporting a large crystal over the face of the instrument panel. The backsplasher incorporates a pair of hinge means which are common to all three portions of the backsplasher.

My invention will be better understood from the following description taken in connection with the accompanying drawings and its scope will be pointed out in the appended claims.

FIGURE 1 is a perspective view of a free standing electric range embodying the present invention.

FIGURE 2 is a plan view of the back portion of the range showing the backsplasher with a series of four multiple pushbutton switches mounted on the top surface

2

thereof for controlling the surface heating units on the cooktop.

FIGURE 3 is a cross-sectional elevational view taken on the line 3—3 of FIGURE 2, and it shows in dotted lines the position of the backsplasher after it has been folded down onto the cooktop.

FIGURE 4 is a cross-sectional elevational view similar to that of FIGURE 3 showing the front crystal frame in its open position and an instantaneous view of the instrument panel moving away from the back cover plate so that the switches, thermostats, and other control components mounted on the instrument panel may be serviced from the front of the range.

FIGURE 5 is a fragmentary perspective view showing one of the multiple hinges for pivoting either the entire backsplasher or only the instrument panel and the front crystal frame in order to obtain the advantages of front-serviceability as well as a compact design for shipment.

Turning now to the drawings and in particular to FIGURE 1 there is shown an electric range 10 comprising a cabinet or body 11 having a cooktop 12 supporting four surface heating units 13. Below the cooktop are ovens 14 and 15 which are closed by drop doors 16 and 17 respectively. The largest oven 15 has a door 17 with a glass window 18 for inspection of the food while it is being cooked. Below each oven is a drawer 19 and 20 for the storage of pots and pans and other cooking utensils.

Across the back edge of the cooktop 12 is formed the backsplasher 21 which embodies the present invention. The purpose of the backsplasher, of course, is to support and enclose the various switches, thermostats, transformers, circuit breakers, and other components for controlling the flow of electricity to the various heating elements of the range. While this invention was discovered during the development of an electric range, it is conceivable that it could be adopted by a gas range manufacturer. The four surface heating elements 13 are controlled by a series of four multiple pushbutton switches 22 which are positioned on the top and at the right side of the backsplasher. Several openings 23 at the right side are access openings for receiving the knobs of the switches and thermostats for controlling the ovens 14 and 15. The openings 24 at the left side of the backsplash accommodate the various knobs of a clock and timer. The backsplasher 21 is supported on a pair of pedestals 25 that are disposed one at each side of the cooktop. Each pedestal 25 is a hollow stationary member through which lead wires (not shown) are fed for connecting the heating elements with their control switches and thermostats.

A better understanding of the backsplasher may be had by studying FIGURE 4 and comparing it with the fragmentary perspective view of FIG. 5. The backsplasher may be considered as being divided into three parts. There is a back cover plate 30, an instrument panel 31 and finally a front crystal frame or trim frame 32 which shields the instrument panel. The back cover plate 30 is supported between a pair of posts 33 which represent extensions of the pedestals 25. A multiple hinge 34 is supported on each pedestal 25 and is connected to each of the three panels of the backsplasher. One leaf 35 of the hinge is bolted to the top front side of the pedestal 25 to serve as a connection between the backsplasher and the range body. A similar leaf 36 is positioned beside the leaf 35 for connection to the post 33 of the back cover plate 30. The instrument panel 31 is likewise connected to the hinge means 34 by means of a leaf 37. Finally, the front crystal frame 32 is connected to the hinge by means of leaf 38 that has a series of 3 pin receiving sections 39, 40 and 41. A common hinge pin 42 extends through all of the leaves of each hinge means 34.

The fixed leaf 35 and the leaf 36 for the post of the back cover plate are disposed on one side of the pivot pin 42 while the leaves 37 and 38 of the instrument panel and crystal frame respectively are disposed on the opposite side of the pivot pin.

Looking now at FIGURE 3 a sheet metal screw 45 is shown at the lower edge of the back cover plate 30 for securing the supporting post 33 to the pedestal 25. When this screw 45 and the similar one on the other side of the backsplash is removed the entire backsplash 21 may be folded down about the axis of the pivot pin 42 until it assumes the horizontal position shown in dotted lines in FIGURE 3. A cardboard block or cushion 46 is also shown in dotted lines resting on the cooktop 12 so that the backsplash bears on the cushion while the range is sealed in its shipping carton.

In order to separate the instrument panel 31 and crystal frame 32 from the back cover plate 30, the backsplasher is first supported in the vertical position and secured by screws 45 as shown in full lines in FIGURE 3. Next as shown in FIGURE 4, the top screws 47 and the front screws 48 are removed so that both the instrument panel 31 and the frame 32 may be folded down onto the cooktop. The crystal frame 32 may be separated from the instrument panel by removing the screws 49 that extend through the back of the panel 31 and into the frame. There is a large flat crystal 50 that is confined within the frame 32 when the frame is fastened to the instrument panel 31.

The instrument panel 31 not only supports thermostats and switches 51 but it also carries the multiple push-button switches 22 in a top extension 53. Moreover a pair of fluorescent lamp holders 54 are fastened to the panel so that a fluorescent lamp may extend nearly the complete length of the backsplasher. The crystal frame 32 includes a housing or reflector 55 for enclosing the fluorescent lamp so that the lamp is recessed within the backsplasher as is best seen in FIGURE 3. The crystal 50 is coated on the back side with a ceramic paint or like material to form an opaque decorative trimming 56 and 57 of FIGURE 1 so that only a portion of the front surface of the instrument panel 31 can be seen from the front of the range. It should be understood that the control knobs 58 and 59 have cylindrical extensions 58' and 59' respectively and are slipped through the openings 23 and 24 in the crystal and then onto the shafts of the switches and thermostats mounted on the instrument panel as seen in FIGURE 3, and that these knobs must be pulled off before the instrument panel 31 can be separated from the crystal frame 32. Hence, it is an easy matter to clean the crystal with a damp cloth since the tips of the shafts of the switches and other components are positioned behind the crystal as is understood by referring to the panel 31 in FIGURE 4 and remembering that the panel 31 is spaced back from the crystal 50 when they stand upright in the normal use position as seen in FIGURE 3.

Having described above my invention of a novel backsplash design which may be serviced from the front it will readily be apparent to those skilled in this art that I have devised a design which is both pleasing in appearance and simple to service through it includes all the latest automatic control and indicator features which are available on the top-of-the line models. While I have not elected to illustrate the maze of wires, switches, circuit breakers, thermostat, pilot lights, etc. which are installed in the backsplash those skilled in this art will understand the complexities of the control system for a range of this size, and will appreciate the unique pivotal action of the backsplasher of this invention for facilitating the ease of gaining access to the components and replacing them when necessary.

Modifications of this invention will occur to those skilled in this art and it is to be understood therefore, that this invention is not limited to the particular em-

bodiment disclosed but that it is intended to cover all modifications which are within the true spirit and scope of this invention as claimed.

What I claim as new and desire to secure by Letters Patent of the United States is:

1. In an electric range including a body having a cooktop, a front-serviceable backsplasher structure arranged adjacent the rear of the cooktop, the backsplasher comprising a back cover plate, an instrument panel fastened to the cover plate, and a crystal frame fastened over the instrument panel, and a multiple hinge means common to the three portions of the backsplasher and supported from the range body, so that the entire backsplasher may be folded down over the cooktop, or only the instrument panel and the crystal frame may be folded down, or alternatively only the crystal frame may be located in its folded down position.

2. A front-serviceable backsplasher structure in a range having a body with a counter height cooktop, the backsplasher being arranged adjacent the rear of the cooktop, the backsplasher being divided into at least three portions, a back cover plate, an instrument panel fastened to the cover plate, and a crystal frame fastened over the instrument panel, and multiple hinge means fixed to the range body for supporting the three portions of the backsplasher so that both the instrument panel and the crystal frame may be folded down, or alternately only the crystal frame may be located in its folded down position over the cooktop, or finally the entire backsplash structure may be folded down so as to reduce the overall height of the range for shipping purposes.

3. A front-serviceable backsplasher for a range as recited in claim 2 wherein the crystal frame supports a large crystal that extends for nearly the entire width of the range, the crystal including apertures aligned with shafts of instruments mounted on the instrument panel, and control knobs having extensions which extend loosely through the apertures for mounting on the said shafts, the front surface of the crystal being free of obstructions when the knobs are removed.

4. In a cooking range having a body with a cooktop at table height, a front-serviceable backsplasher structure arranged on pedestals adjacent the rear of the cooktop, one pedestal being located at each side of the range, hinge means supported on the top of each pedestal, each hinge means comprising multiple leaves, the backsplasher being divided into three pivoted sections that are hinged to the pedestals by the said hinge means, the three portions of the backsplasher being the back cover plate, an instrument panel for supporting various heat controlling means, and a crystal frame positioned over the instrument panel, whereby the entire backsplasher structure may be folded down over the cooktop for shipping purposes, or the instrument panel and crystal frame may be folded down for servicing the range without the range having to be moved, or finally folding down only the crystal frame may be located in its folded down-position.

5. In a range as recited in claim 4, wherein at least one leaf of each hinge means is permanently fastened to the top portion of the adjacent pedestal, a second leaf of each hinge being fastened to the back cover plate while the leaf for the crystal frame has several pin receiving sections which are disposed between and on each side of the two aforementioned leaves of the pedestal and the back cover, and finally a hinge leaf fastened to the instrument panel and being supported on a common pin extending through all of the leaves.

6. In a cooking range as recited in claim 4, wherein the cover plate is fastened to the range body, the instrument panel is fastened to the cover plate and the crystal frame is fastened to the instrument panel although both the instrument panel and the crystal frame must be folded down over the cooking top before the crystal frame may be unfastened from the instrument panel.
